UNITED STATES PATENT OFFICE.

JOHN E. BELL, OF BARBERTON, OHIO, ASSIGNOR TO THE STERLING COMPANY, OF CHICAGO, ILLINOIS, A CORPORATION OF NEW JERSEY.

SUPERHEATER-BOILER.

No. 797,256.

Specification of Letters Patent.

Patented Aug. 15, 1905.

Application filed November 25, 1904. Serial No. 234,106.

To all whom it may concern:

Be it known that I, JOHN E. BELL, of Barberton, Summit county, Ohio, have invented a new and useful Superheater-Boiler, of which the following is a full, clear, and exact description, reference being had to the accompanying drawings, forming part of this specification, in which—

Figure 1 is a vertical longitudinal section showing one form of my improved superheater-boiler; and Figs. 2, 3, and 4 are similar views showing modified forms.

My invention relates to the class of boilers wherein a superheater is located within the setting and is designed to improve the efficiency of the boiler while providing for superheating of the steam.

I have found that by placing at least three banks of water-tubes in front of the superheater and locating the superheater in the last pass of the gases the heat of the gases will be sufficiently extracted and considerable superheat may be obtained. The effect may also be produced to some extent by giving at least three passes to the gases before reaching the superheater, whether these passes are over separate banks of tubes or successive passes over the same bank of tubes.

In the drawings, referring to the form of Fig. 1, I show a boiler having upper transverse steam and water drums 2, 3, and 4, connected by banks of tubes 5, 6, and 7 to the mud-drum 8. The drums 3 and 4 may be connected by water-tubes 9 and steam-tubes 10 and the drums 2 and 3 connected by steam-tubes 11. The gases are given serial passes over banks of water-tubes by the baffles 12, 13, and 14. At the rear of the boiler proper is placed the superheater, which I have shown as comprising an upper steam-drum 15, connected to a lower steam-drum 16 by tubes 17, having a rear baffle 18. The steam is preferably led by pipes 19 from the drum 2 into an end compartment formed by a transverse partition in drum 15 and thence flows down to drum 16 and up to the other compartment—drum 15, whence it may be taken off through outlet 20. The gases flow in serial up and down passes, first over the three banks of water-tubes and then over the superheating tubes and to the stack-flue.

In Fig. 2 I show a form similar to that of Fig. 1, except that the two mud-drums 8^a and 21 are employed. In this view similar parts

are marked with the same number with the letter *a* applied.

In the form of Fig. 3 two steam and water drums 3^b and 4^b are employed, the middle bank of water-tubes 6^b extending from the drum 4^b to the rear mud-drum 8^b, while the front bank of tubes 7^b leads to the front mud-drum 21^b. In this form the two mud-drums may be made in the form of one, so that the tubes 6^b and 7^b become practically a part of the same bank, with a baffle between them to give an up-and-down pass. In this form similar parts are marked with the same numerals with the letter *b* applied.

In Fig. 4 I show a form similar to that of Fig. 1 except that an additional mud-drum 22 is provided with a bank of tubes 23, leading from it up to the rear steam and water drum 2^c. The fourth pass is thus given to the gases before they reach the superheater. In this case parts similar to those of Fig. 1 are marked with the same numeral with the letter *c* applied.

In all the forms the gases from furnace F are given at least three serial passes over water-heating surface formed of water-tubes extending between transverse upper and lower drums before reaching the superheater. I thus place the superheater in a region of low temperature and efficiently extract the heat of the gases, while providing for considerable superheating of the steam.

Variations may be made in the form and arrangement of the boiler and the superheater portion without departing from my invention.

I claim—

1. A boiler having transverse upper and lower drums connected by banks of water-tubes, baffles arranged to give the gases at least three up-and-down passes over said water-tubes, said water-tubes comprising the entire heating-surface of the first three passes and a superheater in the rear of the boiler proper within its setting and in the last pass of the gases; substantially as described.

2. A boiler having transverse upper and lower drums connected by at least three banks of water-tubes, baffles arranged to give the gases serial up-and-down passes over said water-tubes, said water-tubes comprising the entire heating-surface of the first three passes and a superheater in the rear of the boiler proper within its setting and in the last pass of the gases; substantially as described.

3. A boiler having transverse upper and lower drums connected by three banks of water-tubes, baffles arranged to give the gases serial up-and-down passes over said water-tubes, said water-tubes comprising the entire heating-surface of the first three passes and a superheater in the rear of the boiler proper within its setting and in the last and fourth pass of the gases, said superheater compris-

ing upper and lower transverse drums connected by superheating-tubes; substantially as described.

In testimony whereof I have hereunto set my hand.

JOHN E. BELL.

Assignment in Letters Patent No.

It is hereby certified that the name of the assignee in Letters Patent No. 797,256, granted August 15, 1905, upon the application of John E. Bell, of Barberton, Ohio, for an improvement in "Superheater-Boilers," was erroneously written and printed "The Sterling Company," whereas the said name should have been written and printed *The Stirling Company*; and that the said Letters Patent should be read with this correction therein that the same may conform to the record of the case in the Patent Office.

Signed and sealed this 10th day of October, A. D., 1905.

[SEAL.]

F. I. ALLEN,
Commissioner of Patents.

3. A boiler having transverse upper and lower drums connected by three banks of water-tubes, baffles arranged to give the gases serial up-and-down passes over said water-tubes, said water-tubes comprising the entire heating-surface of the first three passes and a superheater in the rear of the boiler proper within its setting and in the last and fourth pass of the gases, said superheater compris-

ing upper and lower transverse drums connected by superheating-tubes; substantially as described.

In testimony whereof I have hereunto set my hand.
